UNITED STATES PATENT OFFICE.

HOWARD G. MACDONALD, OF MURRYSVILLE, PENNSYLVANIA, ASSIGNOR TO WESTINGHOUSE ELECTRIC & MANUFACTURING COMPANY, A CORPORATION OF PENNSYLVANIA.

CIRCUIT INTERRUPTER.

Application filed February 6, 1922. Serial No. 534,378.

To all whom it may concern:

Be it known that I, HOWARD G. MACDONALD, a citizen of the United States, and a resident of Murrysville, in the county of Westmoreland and State of Pennsylvania, have invented a new and useful Improvement in Circuit Interrupters, of which the following is a specification.

This invention relates to circuit interrupters and particularly to means for extinguishing arcs that are formed during the operation of a circuit breaker.

My invention has for its objects the provision of means whereby, during the opening movement of a circuit breaker, the flow of current through the relatively movable contact members is utilized to set up a magnetic field having a powerful blow-out effect for extinguishing arcs when the final break occurs, and to simplify and improve generally the apparatus employed for interrupting circuits of high potential.

To enable the invention to be clearly understood, it will be described with reference to the accompanying drawings which illustrate the invention as applied, by way of example, to a single pole double break oil switch having a moving bridge.

In the drawings, Figure 1 is a sectional elevation of the oil switch constructed in accordance with my invention.

Fig. 2 is a sectional elevation of the switch in a plane at right angles to that of Fig. 1.

Fig. 3 is a plan view of the moving bridge of the switch corresponding to Fig. 1, and

Fig. 4 is a diagrammatic perspective view showing the various contact members of the switch and also the electrical circuit therewith when the switch is being opened.

In the drawings, 1 and 2 represent the fixed main contact members of the switch. These contact members are of inverted substantially U-shaped laminated members arranged parallel with one another and presenting two downwardly directed contact surfaces 3 and 4, in a horizontal plane. The said U-shaped members are firmly secured, for example, by means of screws 5 to the undersides of metal blocks or castings 6 which are supported on the terminal rods 7 and 8, the lower ends of which are provided with screw threads and are adapted to engage in screw threaded sockets 9 on the blocks 6. To en-

sure a good electrical contact and a firm connection between the terminal rods 7 and 8, and the blocks 6, the sockets 9 may be split, as shown in Fig. 1, and clamped on the said terminal rods by means of tangential screws 10. The said rods 7 and 8 are provided with insulating bushings or sleeves 11 and pass up through the main casting or cover 12 of the switch, to which cover the said rods may be secured by means of cement co-operating with a wire banding 13 in flanged bushes 14 secured by means of bolts 15, or otherwise, in perforations in the casting or cover 12.

The terminal rods 7 and 8 which will be provided with terminals or other connections at their upper ends, are arranged in parallel relation with respect to one another, as shown clearly in Figs. 1 and 2, and for convenience of construction are set in a plane inclined to the center axis of the switch, although it will be understood that they may be otherwise disposed.

Stay rods 16 are interposed between metal seatings 17 on the blocks or castings 6 (see Figs. 1 and 2), and adjustable plugs 19 having square or other shaped heads 20 permitting the said plugs to be externally rotated in the cover or casting 12 for adjusting the compression on the rods 16. The stay rods may be provided with ball ended sockets 18.

The bridge which co-operates with the contact surfaces 3 and 4 of the fixed main contact members 1 and 2 is indicated at 21 and comprises, according to a preferred construction, a rigid rectangular metal frame 90 having, at each corner, an enlargement 22 constituting contact surfaces parallel with, and adapted to engage, the aforesaid downwardly presented contact surfaces 3 and 4 of the fixed contacts 1 and 2.

The frame 21 is formed with diagonal, parallel or other cross webs 23 (as shown most clearly in Fig. 3) by means of which it is secured to the lower end 24 of the vertical switch operating rod 25 in such manner as to move in a vertical direction for closing and opening the switch.

The actuating rod 25 is provided with an extension 26 passing through a guide bushing 27 forming part of, or secured to, the casting or cover 12. The movements required for opening and closing the switch may be imparted to the extension rod 26 by

means of actuating mechanisms or solenoids in any familiar manner, a description thereof being deemed unnecessary since such operating means form no part of the present invention.

Two insulating plates 28 are arranged in parallel planes between the terminal rods 7 and 8 and spaced apart a sufficient distance to permit the switch operating rod 25 to pass therebetween. Advantageously, the said plates are bolted to downwardly extending webs 29 integral with, or bolted to, the underside of the main casting or switch cover 12, as shown most clearly in Fig. 2.

15 The shunt or arcing contact members are arranged at the corners of a parallelogram which is angularly displaced with relation to the rectangular bridge frame 21. The moving shunt contact members are indicated 20 at 31, 32, 33 and 34, and, as clearly shown in the drawings, are secured at the centers of the sides of the frame 21 from which they are separated by insulating plates 35. The said moving shunt contact members advantageously comprise copper or brass headed studs secured by means of nuts 36 in sockets 37 formed with lateral portions 38 and secured by means of set screws 39 to the outer faces of the said frame 21, insulating bushings 40 passing through said lateral portions 38 and surrounding said set screws 39, as shown in detail section in the lower left-hand corner of Fig. 1. Transverse screws 40a may be inserted in tapped holes from 35 the underside of the frame 21 to lock the said screws 39 in position.

The fixed shunt contact members which co-operate with, and are adapted to be engaged by, the above described moving shunt contact members 31 to 34 are indicated at 40 41, 42, 43 and 44 and are arranged as follows. Two of the said fixed contact members, namely, 41 and 44, which are diagonally opposite one another, are supported 45 upon the blocks or castings 6 (see Figs. 2 and 4). The said contact members 41 and 44 are carried upon rods 45 arranged to slide in brackets 46 attached to, or cast integral with, the blocks or castings 6. Springs 47 50 are provided upon the rods 45 and they tend to urge the contact members 41 and 44 downwards, split pins or any other form of stops 48 being provided on the upper ends of the rods 45 to limit the downward movement thereof. The above construction or 55 any other form of lost motion may be employed in the shunt contact members to ensure their opening after the main contact members.

60 The other diagonally opposite pairs of fixed shunt contact members 42 and 43 which co-operate with the moving contact members 32 and 33 are slidably mounted in brackets 49 in an exactly similar manner 65 as are the contact members 41 and 44 just

above described. The brackets 49, however, (as shown in Fig. 1) are supported between the insulating plates 28 and are secured to the latter by means of bolts or screws 50, or otherwise. The said contact members 42 and 43 will thus be completely insulated from any other part of the switch. Flexible conductors 51 may be provided between the brackets 46 and 49 and the contact members 41 to 44, respectively, to ensure good electrical connection between these members.

70 The electrical connections of the shunt or arcing contact members are as follows. The two diagonally opposite fixed contact members 41 and 44 are in electrical connection with the terminal rods 7 and 8 while the other diagonally opposite fixed contact members 42 and 43 carried by the insulating plates 28 are electrically connected together by means of one or more conductors 52 (see 75 Figs. 1 and 4) extending from one side of the switch to the other between said insulating plates. Such conductors 52 advantageously comprise wires, strips or flexes of copper protected by insulating beads or 80 tubes (not shown).

85 The contact members 31 to 34 of the moving shunt contact members carried by the bridge frame 21 are not diagonally connected but are connected in adjacent pairs, that is to say, the contact member 31 is connected with the contact member 32 and the contact member 33 with the contact member 34. Such connection may advantageously be provided by means of one or more wires, strips or flexes 53 of copper protected by insulating beads or tubes 54, as clearly 90 shown in Fig. 3. The main oil tank of the switch is indicated at 55.

95 Referring now to Fig. 4, which illustrates the contact members in a somewhat distorted perspective form for the sake of clearness, it will be seen that the two main breaks of the switch are respectively between the flexible member 1 and the enlargements 22 at 100 the left hand end of the bridge frame 21 and between the enlargements 22 at the right hand end of the bridge frame 21 and the flexible contact member 2 while, upon opening the switch, the main contact members first separate and after a predetermined movement of the bridge the shunt contact members separate, the circuit then momentarily passing through said shunt contact members and the four arcs, that is, from the 105 fixed contact member 41, connected to one terminal rod, to the moving contact member 31 through the arc therebetween, along the conductors 53 to the moving contact member 32 thence to the contact member 42 by 110 way of the arc between these contact members, through conductors 52 to contact member 43, then from contact member 43 to contact member 33 by way of the arc between 115 these contact members, through conductors 120 125 130

53 to contact member 34 and from contact member 34 to contact member 44 by way of the arc between these contact members, and thence to the other terminal rod. Such a 5 circuit is clearly shown in perspective by the dotted line in Fig. 4. The circuit through the shunt contact members and the four arcs is thus in the form of two coils or convolutions whereby a strong magnetic field 10 will be produced with a correspondingly powerful blow-out effect upon the arcs which will thus be quickly extinguished when the final breaks occur, that is, when the bridge frame 21 has moved down to a sufficient extent.

It will be understood that numerous modifications may be made in the construction and disposition of the parts of the switch without departing from the scope of the invention. For example, although the fixed contact members 1 and 2 are provided with two contact surfaces 3 and 4, and are made flexible by laminations, single contact members of the butt or other type, or more than 25 two breaks, may be employed, the essential feature of the invention being that the switch is provided with shunt or arcing contact members arranged to provide a shunt circuit having a tortuous path when the 30 switch is being opened. It will also be understood that the invention is not confined in its application to oil switches.

I claim as my invention:

1. In a circuit interrupter, the combination with a plurality of relatively movable main contact members, of a plurality of arcing contact members, a plurality of arcing contact members movable relative to the first-named arcing contact members, and a tortuous electrical connection between the said relatively movable arcing contact members, whereby a magnetic blow-out field is set up in the zone therebetween.

2. In a circuit interrupter, the combination with a plurality of relatively movable main contact members, of a plurality of relatively movable arcing contact members having tortuous electrical connection therebetween whereby a magnetic blow-out field 50 is set up.

3. The combination with two groups of relatively movable contact members, the contact members of each group being spaced apart in both longitudinal and transverse 55 directions, of electrical connections between adjacent contact members, whereby a path of current is established through the contact members of the respective groups alternately.

4. In a circuit interrupter, the combination with a pair of main stationary contact members and a movable bridging member, of a pair of arcing tips mounted on stationary supports and having electrical connection 65 to the main contact members, a second pair

of arcing tips mounted on stationary supports and insulated from the first-named arcing tips but having electrical connection with one another, a pair of electrically-connected arcing tips carried by the bridging member and positioned to engage one tip of each of the first-mentioned two pairs of tips, and a second pair of electrically-connected arcing tips carried by the bridging member and positioned to engage the other 75 tip of each of the first-mentioned two pairs of tips.

5. In an electric circuit, the combination with a group of four contact members arranged in the form of a quadrilateral and 80 a second group of relatively movable contact members similarly arranged and positioned to co-operatively engage the first-named group, of an electrical connection between two diagonally disposed contact members of one group and electrical connections between the two contact members at opposite sides of the other quadrilaterally arranged group.

6. In an electric circuit, the combination 90 with a group of spaced contact members and a second group of spaced relatively movable contact members positioned to co-operate with the first-named group, of electrical connections between diagonally disposed contact members of one group and an 95 electrical connection between two contact members of the other group, one of which contact members co-operates with one of the said diagonally disposed members. 100

7. In a circuit breaker, the combination with a pair of main contact members and a relatively movable bridging member, of a pair of auxiliary contact members conductively connected to the bridging member, 105 a pair of contact members carried upon, and insulated from, the bridging member and conductively connected to the first said contact members respectively, an auxiliary contact member conductively connected to each 110 of the main contact members for respectively engaging the first said auxiliary contact members and a pair of auxiliary conductively-connected contact members for engaging 115 respectively the second pair of auxiliary contact members.

8. In a circuit breaker, the combination with a pair of main contact members and a relatively movable bridging member, of auxiliary contact members for maintaining 120 the circuit in closed condition after the bridging member has been disengaged from the main contact members, the contact members of one pair of said auxiliary contact members being insulated from and carried 125 by the main contact members and the bridging member.

9. In a circuit breaker, the combination with a pair of main contact members and a relatively movable bridging member, of 130

relatively movable auxiliary contact members carried by the main contact member and the bridging member for maintaining the circuit in closed condition after the bridging member has been disengaged from the main contact members, certain of the said auxiliary contact members being insulated from the main contact members and

the bridging member and all auxiliary contact members being connected to constitute 10 a tortuous conductive path whereby a magnetic blow-out field is set up.

In testimony whereof, I have hereunto subscribed my name this 24th day of January, 1922.

HOWARD G. MacDONALD.
